US00D818029S

(12) **United States Design Patent** (10) **Patent No.:** **US D818,029 S**
(45) **Date of Patent:** **** May 15, 2018**

(54) **DIGITAL CAMERA**

(71) Applicant: **Nikon Corporation**, Tokyo (JP)

(72) Inventors: **Chikara Fujita**, Tokyo (JP); **Hiroyuki Asano**, Tokyo (JP)

(73) Assignee: **Nikon Corporation**, Tokyo (JP)

(**) Term: **15 Years**

(21) Appl. No.: **29/610,814**

(22) Filed: **Jul. 15, 2017**

(57) **CLAIM**

The ornamental design for a digital camera, as shown and described.

DESCRIPTION

FIG. 1 is a front, top and right side perspective view of a digital camera showing our new design;
FIG. 2 is a rear, bottom and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines illustrate portions of the digital camera and form no part of the claimed design.

1 Claim, 8 Drawing Sheets
